AIR STRAINER FOR HORNS

Sidney G. Down, Edgewood, Pa., assignor to The Westinghouse Air Brake Company, Wilmerding, Pa., a corporation of Pennsylvania

Application October 9, 1931. Serial No. 567,837

13 Claims. (Cl. 116—137)

This invention relates to air strainers and more particularly to an air strainer adapted for use in conjunction with pneumatic horns to prevent the admission of foreign matter into the dia-

5 phragm chamber of the horn.

One object of the present invention is the provision in a pneumatic horn of improved means for positioning and retaining an air strainer in the horn bracket.

10 Another object resides in the provision of an air strainer adapted to be readily applied to or removed from the pneumatic horn to facilitate its inspection, cleaning, and replacement.

A further object lies in the improved construction and arrangement of parts which provide a horn capable of being manufactured at a comparatively low cost.

Other objects and advantages will appear from the following description of an illustrative embodiment of the present invention.

In the drawing, Fig. 1 is a sectional view through a pneumatic horn taken on the line 1—1 of Fig. 2; and Fig. 2 is a rear elevational view of a pneumatic horn, embodying my invention, with parts broken away to more clearly show its construction.

The pneumatic horn, to which the air strainer of the present invention is applied, comprises a body portion 10 having a pair of fluid pressure chambers containing flexible diaphragms (not shown) by the operation of which sounds are produced. A mounting bracket 11 is formed integral with the body portion 10 and is provided with an extended flat base 12 perforated to receive 35 anchor bolts for securing the horn to any suitable support.

A chamber 13, formed in the mounting bracket 11, is provided with a pair of screw-threaded apertures 14 (one of which is shown) adapted to selectively receive a supply pipe 15 for delivering fluid under pressure to the horn from any suitable source of supply. A pipe plug 16 serves as a closure for the unused opening 14 which serves as a drain opening. A bore 17 extending inwardly from its open end in the side face of the bracket connects the chamber 13 with a chamber 18 formed in a boss 19 on the side of the mounting bracket. A pair of passages 20 and 20' of 50 relatively small capacity compared with the supply pipe, provide open communication between the chamber 18 and chambers 21 and 21', respectively. A port 22 formed in the wall of chamber 21 leads to one of the fluid pressure chambers 55 of the pneumatic horn. The chamber 21' com-

municates in a similar manner with the other fluid pressure chamber of the horn.

The air strainer, which serves to prevent the admission of foreign matter to the diaphragm chamber of the horn, is positioned in the bore 17 and comprises a mass of suitable straining material 23 such as curled hair held in place by a pair of perforated discs 24, the flow area of the perforations being greater than that of the combined passages 20 and 20'. The strainer is positioned in the bore 17 by inserting a disc 24 through an opening 25 in the boss 19. The disc is seated against a flange 26 formed in the bore 17 and curled hair or the like is placed in the bore 17. A second perforated disc 24, is then placed in the bore and retained by the application of a spring ring 27, which seats in a groove 28 formed in the wall of the bore 17. In this manner, the straining material is confined within the bore 17 by the discs 24 and forms a mass of porous material through which fluid under pressure is passed so as to remove foreign matter from the fluid prior to the admission of the fluid to the pressure chambers of the pneumatic horn. After the strainer has been properly positioned in the bore 17 of the horn bracket, a plug 29 is screwed into the opening 25 to form a closure for the chamber 18.

In operation, fluid under pressure is admitted to the chamber 13 through the usual supply pipe 15 and flows to the chamber 18 after passing through the bore 17 containing the strainer which is adapted to collect all foreign matter contained in the fluid as the fluid passes at a relatively slow velocity through the strainer. From the chamber 18, the fluid passes through passages 20 and 20' to chambers 21 and 21', respectively, and thence through ports 22 (one of which is shown in the drawing) to the diaphragm chambers formed in the horn body 10. As pressure is built up in the diaphragm chambers, the horns function in the usual manner.

It has been found that the application of a strainer element to the horn has eliminated the admission of foreign matter to the diaphragm chamber of the horn and thus materially increased its serviceability. From time to time, it is advisable to replace the strainer material which, in operation, becomes impregnated with foreign matter. This replacement may readily be effected by removal of the plug 29 which makes the strainer element accessible. The spring ring 27 may then be displaced and the discs 24 and curled hair 23 may be easily withdrawn from the bore 17 through the opening 25 formed in the

boss 19 of the mounting bracket 11. The mass of straining material may then be cleansed of its foreign matter, or replaced by new material and the strainer repositioned in the bore 17 in the manner previously described, and upon replacing the plug 29 the horn will again be ready for use.

It will readily be seen that an improved pneumatic horn has been provided in which a strainer element has been embodied to insure long periods of satisfactory operation by eliminating the admission of foreign matter to the diaphragm chambers of the horn, which in the past has been a source of difficulty. It will also be seen that the strainer element of the present invention is readily accessible for inspection, repair or replacement without necessitating the removal of or dismantling of the horn to effect the desired operation.

While the invention has been described in considerable detail in the foregoing specification, it will be understood that various changes may be made in its embodiment without departing from or sacrificing any of the advantages as herein-after claimed.

Having now described my invention, what I claim as new and desire to secure by Letters Patent, is:

1. The combination with a sound producing device comprising a body portion provided with a diaphragm chamber and having a mounting bracket formed integral with said body portion and having an attaching face and a side face and provided with a bore accessible from the side face, through which fluid is supplied to said diaphragm chamber, of a strainer mounted in said bore for removing foreign matter from fluid supplied to said chamber.

2. The combination with a sound producing device comprising a body portion provided with a diaphragm chamber and having a mounting bracket formed integral with said body portion and provided with a bore, through which fluid is supplied to said diaphragm chamber, of a strainer mounted in said bore for removing foreign matter from fluid supplied to said chamber, said bore having an atmosphere opening through which said strainer may be removed, and a removable plug for closing said opening.

3. The combination with a sound producing device comprising a body portion provided with a diaphragm chamber and having a mounting bracket formed integral with said body portion and having an attaching face and a side face and provided with a bore accessible from the side face, through which fluid is supplied to said diaphragm chamber, of a strainer comprising a mass of pervious material adapted to be received in said bore, and means for retaining said strainer in said bore.

4. The combination with a sound producing device comprising a body portion provided with a diaphragm chamber and having a mounting bracket formed integral with said body portion and provided with a bore through which fluid is supplied to said diaphragm chamber, of a strainer comprising a mass of pervious material adapted to be received in said bore, and means for retaining said strainer in said bore, said bore having an atmosphere opening through which said strainer may be removed, and a removable plug for closing said opening.

5. The combination with a pneumatic horn, of a strainer for removing foreign matter from fluid supplied to said horn, said horn comprising a body portion provided with a diaphragm cham-

ber and having a mounting bracket formed integral with said body portion provided with an attaching face and a side face and provided with a bore accessible from the side face, through which fluid is supplied to said diaphragm chamber and means for retaining said strainer in said bore.

6. A pneumatic horn comprising a body portion, a diaphragm chamber in said body portion, a mounting bracket formed integral with said body portion and having an attaching face and a side face provided with an opening, a straining chamber in said mounting bracket communicating with the diaphragm chamber and the said opening, a strainer in said strainer chamber adapted to remove foreign matter from fluid supplied to said diaphragm chamber and accessible through the said opening, and means for releasably retaining said strainer in said strainer chamber.

7. A pneumatic horn comprising a body portion, a diaphragm chamber in said body portion, a mounting bracket formed integral with said body portion, a bore in said mounting bracket, a strainer in said bore adapted to remove foreign matter from fluid supplied to said diaphragm chamber, means for releasably retaining said strainer in said bore and removable means associated with said bore adapted to facilitate the application of said strainer to said bore.

8. A pneumatic horn comprising a body portion, a diaphragm chamber in said body portion, a mounting bracket formed integral with said body portion and having an attaching face and a side face having an opening, a strainer chamber in said mounting bracket communicating with said diaphragm chamber and said opening, a strainer in said strainer chamber adapted to remove foreign matter from fluid supplied to said diaphragm chamber, and accessible through the said opening said strainer comprising a mass of pervious material, perforated means for confining said mass of pervious material, and a removable closure for said opening.

9. A pneumatic horn comprising a body portion, a diaphragm chamber in said body portion, a mounting bracket formed integral with said body portion, a bore in said mounting bracket, a strainer in said bore adapted to remove foreign matter from fluid supplied to said diaphragm chamber, said strainer comprising a mass of pervious material, perforated means for confining said mass of pervious material, means for releasably retaining said strainer in said bore, and a removable plug associated with said bore to facilitate application of said strainer to said bore.

10. A sound producer comprising a casing having a pair of diaphragm chambers, a mounting bracket formed integral with said casing and having an attaching face and a side face provided with an opening and having a strainer chamber through which fluid under pressure is supplied to separate passages leading to said diaphragm chambers, and a fluid strainer mounted in said strainer chamber and accessible through said opening.

11. A fluid actuated acoustic signal comprising a supply pipe, a casing having a strainer chamber connected with the supply pipe and a diaphragm chamber connected with the strainer chamber by a passage of relatively small flow area, and a strainer within the strainer chamber through which fluid flows from the supply pipe to the said passage and diaphragm chamber, the said strainer having a relatively large flow area relative to that of the said passage.

12. A fluid actuated acoustic signal comprising

ing a supply pipe, a casing having a strainer chamber connected with the supply pipe and communicating with an opening in the said casing and a diaphragm chamber connected to the strainer chamber by a passage accessible through said opening, a strainer within the strainer chamber through which fluid flows from the supply pipe to the said passage and diaphragm chamber, the said strainer being accessible through the 10 said opening, and a closure for the said opening.

13. The combination with a sound producing

device comprising a body portion provided with a diaphragm chamber and having a mounting bracket provided with a bore, through which fluid is supplied to said diaphragm chamber, of a strainer mounted in said bore for removing foreign matter from fluid supplied to said chamber, said bore having an atmospheric opening through which said strainer may be removed, and a removable plug for closing said opening.
